UNITED STATES PATENT OFFICE.

CARLTON H. WHITE, OF WEBSTER, MASSACHUSETTS.

SHADE-HANGER.

No. 926,830.

Specification of Letters Patent.

Patented June 29, 1909.

Application filed November 16, 1908. Serial No. 462,818.

To all whom it may concern:

Be it known that I, CARLTON H. WHITE, citizen of the United States, residing at Webster, in the county of Worcester and 5 State of Massachusetts, have invented certain new and useful Improvements in Shade-Hangers, of which the following is a specification.

This invention comprehends certain new 10 and useful improvements in window attachments, and the invention has for its object a simple, durable and efficient construction of shade hanger which may be applied to a window frame without marring the same, 15 which is susceptible of being quickly and conveniently detached therefrom when house-cleaning or other occasion demands, and which possesses certain other advantages that will become at once apparent as 20 the invention is hereinafter disclosed, over the ordinary shade supports in general use.

With this and other objects in view that 25 will more fully appear as the description proceeds, the invention consists in certain constructions and arrangements of the parts that I shall hereinafter fully describe, and then point out the novel features thereof in the appended claims.

For a full understanding of the invention 30 and the merits thereof, and to acquire a knowledge of the details of construction, reference is to be had to the following description and accompanying drawing, in which:

35 Figure 1 is a perspective view of a window casing equipped with my improved shade hanger; Fig. 2 is a front elevation of the hanger; Fig. 3 is a transverse section on the line 3—3 of Fig. 2; and, Fig. 4 is a detail 40 perspective view of the clamp.

Corresponding and like parts are referred 45 to in the following description and indicated in all the views of the drawing by the same reference characters.

50 My improved shade hanger is designed to be applied to the upper rail or top of a window casing A, and comprises a cross bar 1 constructed of an integral strip of suitable metal having its ends angularly and forwardly disposed to constitute spring brackets 2 which are spaced apart a distance substantially equal to the length of the shade roller to be supported, and which are formed with openings 3 extending therethrough for the reception of the end gudgeons of the

roller, the said brackets being adapted to be sprung apart to permit the gudgeons to be inserted through the openings 3, when desired.

As the preferred means of supporting the cross bar 1, I provide suspension members 4 which, in the present instance are formed of integral strips of suitable wire that are hooked or looped at their lower ends through openings formed in the opposite ends of the cross bar and that are formed at their other or upper ends with rearwardly disposed downwardly facing hooks 5 adapted to penetrate the upper edge of the top of the window casing to suspend the cross bar 1 therefrom. In order to further secure the cross bar in position and prevent it from becoming accidentally detached upon receiving a jar, a clamp 6 is carried by the cross bar at the middle thereof, and in the present instance, is formed of a suitable length of wire which is attached to the cross bar by being wrapped thereabout at one end. The wire passes forwardly through an opening formed in the cross bar, as shown, and extends longitudinally thereof for a predetermined distance, and is then bent to constitute a spring coil 7, the wire being extended downwardly and obliquely beyond the spring coil to form a yielding clamping arm 8 which terminates in a rearwardly extending upwardly disposed spur 9. This spur is designed to be embedded in the lower edge of the top of the window casing and held in such engagement against the tension of the arm 8 and the spring coil 7, and thus serves to exert a downward tension upon the cross bar and the suspension members 4 thereof, to prevent the accidental detachment of the hooks 5.

In the practical use of my improved shade hanger, when occasion demands the removal of the same from the window casing, as in moving or house-cleaning or the like, the clamping arm 8 is swung downwardly against the tension of the spring coil 7, so as to disengage the spur 9 from the lower edge of the top of the window casing A, whereupon the cross bar 1 may be moved upwardly to disengage the hooks 5 from the upper edge of the top of the casing and effect the expeditious removal of the entire device therefrom, without the necessity of expending time and labor in removing screws or nails or similar fastening means, as is required with the shade brackets in general use. Furthermore,

since the fastening means are engaged with the upper and lower edges of the top of the window casing, and not with the front face thereof, in the usual manner, it will be observed that with this improved device, the window casing is not noticeably marred or disfigured.

From the foregoing description, in connection with the accompanying drawing, it will be apparent that I have provided an improved shade hanger which is susceptible of being conveniently applied to and detached from a window casing, and is arranged to support the shade securely in position against any accidental detachment; which embodies, to a marked degree, the characteristics of simplicity, durability and strength, and which consists of comparatively few parts that may be easily and cheaply manufactured and readily assembled.

Having thus described the invention, what I claim is:

1. A shade hanger comprising a cross bar arranged to engage and support a shade roller, suspension means carried by the cross bar on one side thereof, and a clamp also carried by the cross bar and embodying a spring clamping or engaging arm disposed on the

opposite side of the cross bar from the suspension means.

2. A shade hanger comprising a cross bar arranged to engage and support a shade roller, suspension members secured at one end to the cross bar and terminating at their other ends in hooks, and a clamp also carried by the cross bar and embodying a spring engaging or clamping arm disposed on the opposite side of the cross bar from the suspension members and terminating in a spur facing in the opposite direction to the said hooks.

3. A shade hanger comprising a cross bar arranged to engage and support a shade roller, suspension means carried by the cross bar, and a spring clamp also carried by the cross bar and constructed of an integral strip of wire attached to the cross bar at one end and bent to form a tension coil and a yielding engaging or clamping arm terminating in a spur.

In testimony whereof I affix my signature in presence of two witnesses.

CARLTON H. WHITE. [L. s.]
